Inventor

William Donaldson

UNITED STATES PATENT OFFICE.

WILLIAM DONALDSON, OF DETROIT, MICHIGAN.

BOTTLE CARRIER AND COVER.

Application filed November 7, 1925. Serial No. 37,554.

The present invention relates to a bottle carrier and cover, and aims to provide a novel and improved device of this character which may be conveniently attached to a 5 bottle for efficiently covering the top thereof and providing a handle for permitting the convenient carrying of the bottle.

Another object of the invention is the provision of a device as above indicated, 10 having spring jaws arranged thereon which may be sprung to engage about the neck of a bottle below the bead formed on the top thereof, said jaws carrying a portion of the cover, while another portion of the cover 15 is arranged in place afterward for insuring against accidental disengagement of the device from the bottle.

A further object of the invention is to provide an elongated loop having approximately one-half thereof arranged at right angles to the other half, and having jaws formed upon one angled portion of said loop adjacent the point where said loop is angled for engaging about the neck of a bottle, 25 while the other angled portion forms a handle. One of said angled portions of said loop rigidly carries a portion of the cover, while the other angled portion slidably carries the other portion, which when in place 30 entirely covers the top of the bottle, thus forming a sanitary bottle carrier.

It is also an object of the invention to provide a device as above outlined, which is simple and substantial in construction, 25 which can be manufactured economically, and which will be thoroughly efficient and practical in use.

With the foregoing and other objects in view, which will be apparent as the description proceeds, the invention resides in the construction and arrangement of parts, as hereinafter described and claimed, it being understood that changes can be made within the scope of what is claimed, without departing 45 from the spirit of the invention.

The invention is illustrated in the accompanying drawings, wherein:—

Figure 1 is a perspective view of my improved device, showing the same applied to 50 a bottle and showing a portion of the cover raised,

Figure 2 is a top plan view of the same, and

Figure 3 is a fragmentary view of a bottle 55 showing the device completely arranged thereon and ready for use.

Referring to the drawing, the numeral 10 indicates a bottle, and more particularly a milk bottle, which is of the usual construction, having a reduced neck portion 11 and 60 a bead 12 formed upon the upper end of the neck portion. In carrying out my invention, the numeral 15 designates a loop shaped member constructed of a relatively heavy spring wire, said wire having the ends thereof joined, as at 16, by turning one end of the wire over the opposite end of the wire and providing a head 17 on said opposite end. The loop-shaped wire 15 has approximately one-half portion thereof arranged at 70 right angles to the other half portion, so as to provide a handle portion 18 and a bottle engaging portion 19. The bottle engaging portion 19 is slightly larger than a semi-circle, so as to conform generally to the 75 curvature of the neck 11 of the bottle, the handle portion 18 has the side portions 20 thereof gradually converging as they extend upwardly and arranged at right angles to the end portion 21 thereof. The bottle engaging portion 19 has the portions 22 thereof adjacent the portion where the loop is angled turned slightly inward towards each other so as to provide spring jaws which contact with the neck of the bottle beneath 80 the bead 12, while the side portions 20 of the angled handle portion 18 have their lower ends curved inwardly so as to permit the same to extend around the bead 12 when the jaw portions engage the neck of the bottle. 85

A cover is arranged for covering the top of the bottle 10, and is arranged in two sections, one section being carried by the bottle engaging portion of the loop 15 while the other section is arranged on the handle portion 18 of the loop 15. The cover section 23 carried by the bottle engaging portion 19 of the loop is provided with a flat top wall 24 having depending therefrom a flange portion 25 which conforms generally to the 100 curvature of the bead 12 of the bottle, said flange having formed on its lower edge slightly spaced from the ends of the same a rolled portion 26, which engages around the bottle engaging portion 19 of the loop for rigidly securing the cover section 23 to said portion 19. The other section of the cover for the bottle is of a similar configuration, having a top wall 27, right angled depending flange portions 28 extending downwardly from said top wall, and a pair of outstanding ears 29 on opposite sides thereof 105 110 115 120 125 130 135 140 145 150 155 160 165 170

2

which are provided with slots 30 for receiving the side portions 20 of the handle portion 18 of the loop 15. The cover section carried by the handle portion 18 is rolled, as at 31, at the lower edge of the flange 28 so as to give a finished appearance, and has provided on the top wall thereof a U-shaped finger engaging loop 32 for slidably raising said cover section upon said handle portion 18. In order that the cover section carried by the handle portion 18 may normally remain in a downward position over the top of the bottle, I have provided a pair of coil springs 33, one being arranged upon each of said side portions 20 of said handle portion 18 and engaging said outstanding ears 29 forcing said cover section downwardly. By providing the slots 30 in the ears 29, the jaws formed on the bottle engaging portion 19 of the loop 15 are permitted to be forced outwardly, yet providing a structure for slidably mounting one-half of the cover upon the handle portion 18. It is to be noted that by attaching the ends of the wire that form the loop 15 at a point where said loop is angled that a shoulder is provided, as shown by the numeral 16, for engaging under the bead 12 of the bottle, eliminating to a great extent the liability of my improved device from being accidentally disengaged from a bottle. It is also to be noted that by attaching the depending flange 25 of the cover section 23 remote from the point where said cover section 23 engages the other cover section, that a greater resiliency is provided for the jaws that contact with the neck of the bottle.

In operation, the cover section carried by the handle portion 18 is raised upwardly upon said handle portion 18 by engaging the finger loop 32. The spring jaws are then forced around the bottle under the bead 12 thereof, sliding the top flat portion 24 of the cover section 23 over one-half of the top of the bottle, until the flange portion 25 of the cover section 23 abuts against said bead 12. The finger engaging loop 32 is then released, and the cover section carried by the handle 18 is forced downwardly by the coil springs 33, until the flat surface 27 of the last mentioned cover section lies flat upon the top of the bottle not enclosed by the section 23. It can thus be seen that the entire top of the bottle is covered, which will form a sanitary covering for the bottle. When the section of the cover carried by the handle 18 is in an operative closed position, the same will prevent accidental disengagement of the device from the bottle, due to the fact that the flange 28 thereof eliminates sliding movement of the jaws from the bottle. It is to be noted that by providing the slots 30 in the outstanding ears 29 that the side portions 20 of the handle are permitted to flex outwardly with the jaws during the placing

of the device on a bottle and during the removing of the device. After the device is arranged upon the top of a bottle, the bottle may be carried by gripping the portion 21 of the handle 18, thus eliminating to a great extent the danger of dropping the bottle.

Having thus described my invention, what I claim as new is:—

1. A bottle carrier and cover comprising a bottle engaging portion, a handle portion, a cover for the bottle arranged in sections, one of said sections being carried by said bottle engaging portion, while the other section is carried by said handle portion and movably arranged thereon for coacting with said first mentioned section for entirely covering the top of the bottle. 75

2. A bottle carrier and cover comprising a bottle engaging portion, a handle portion, a cover for the bottle arranged in sections, one of said sections being carried by said bottle engaging portion, while the other section is carried by said handle portion and movably arranged thereon for coacting with said first mentioned section for entirely covering the top of the bottle, and means arranged upon said movable section for engaging the bottle for preventing disengagement of said bottle engaging portion from the bottle. 80

3. A bottle carrier and cover comprising a bottle engaging portion adapted to engage about the neck of the bottle, a cover for the bottle arranged in sections, one of said sections being carried by the bottle engaging portion, while said other section is movable and arranged to coact with the first mentioned section for entirely covering the top of a bottle. 95

4. A bottle carrier and cover comprising a cover arranged in sections, a pair of spring jaws carried by one cover section and adapted to engage about the neck of a bottle for holding said section in place, while the other section is movably arranged for coacting with said first mentioned section for entirely covering the top of a bottle. 100

5. A bottle carrier and cover comprising a cover arranged in sections, spring jaws carried by one of said sections and being adapted to engage about the neck of a bottle for holding said sections in place, means carried by said spring jaws for movably supporting the other of said sections to permit the same to be moved to a position to coact with said first mentioned section in order to entirely cover the top of a bottle. 115

6. A bottle carrier and cover comprising a cover arranged in sections, spring jaws carried by one of said sections and being adapted to engage about the neck of a bottle for holding said sections in place, means carried by said spring jaws for movably supporting the other of said sections to permit the same to be moved to a position to coact 120

with said first mentioned section in order to entirely cover the top of a bottle, and means carried by said movable section engaging the top of the bottle for preventing disengagement of said spring jaws from the bottle.

7. A bottle carrier and cover comprising a cover arranged in sections, spring jaws carried by one of said sections for folding the same in position over a portion of the top of the bottle, a handle carried by said jaws, means arranged upon the other of said sections of said cover for slidably supporting same upon said handle for permitting said second mentioned cover section to be moved in position to coact with said first mentioned section for entirely covering the top of a bottle.

8. A bottle carrier and cover comprising a cover arranged in sections, spring jaws carried by one of said sections for folding the same in position over a portion of the top of the bottle, a handle carried by said jaws, means arranged upon the other of said sections of said cover for slidably supporting same upon said handle for permitting said second mentioned cover section to be moved in position to coact with said first mentioned section for entirely covering the top of a bottle, and spring means arranged upon said handle and engaging said second mentioned cover section for normally holding the same in operative position upon a bottle.

9. A bottle carrier and cover comprising a wire arranged in looped formation and having approximately one-half thereof arranged at right angles to the other half, spring jaws formed on one angled portion of said loop adjacent the point of angle for engaging the neck of a bottle while said angled portion having said spring jaws extending around said neck, a cover arranged in sections, one of said sections being permanently carried by a portion of said loop extending around the neck of the bottle, while the other section of said cover is movably carried by the other angled portion of said loop and arranged to coact with said first mentioned section for entirely covering the top of a bottle.

10. A bottle carrier and cover comprising a wire arranged in looped formation and having approximately one-half thereof arranged at right angles to the other half, spring jaws formed on one angled portion of said loop adjacent the point of angle for engaging the neck of a bottle while said

angled portion having said spring jaws extends around said neck, a cover arranged in sections, one of said sections being permanently carried by a portion of said loop extending around the neck of the bottle, while the other section of said cover is movably carried by the other angled portion of said loop and arranged to coact with said first mentioned section for entirely covering the top of a bottle, and spring means arranged upon the angled portion of said loop having said movable section of said cover thereon for normally holding said movable section of said cover in a closed operative position.

11. A bottle carrier and cover comprising a wire arranged in looped formation and having approximately one-half portion thereof arranged at right angles to the other half portion, spring jaws formed upon one angled portion of said wire loop adjacent the point of angle for engaging the neck of a bottle, a cover arranged in sections, one of said sections being carried by the angled portion of said loop having said jaws formed thereon for covering a portion of the top of the bottle, outstanding eyes carried by the other of said sections and receiving the side portions of the angled portion of said loop not having said jaws thereon for slidably supporting said second mentioned cover section for coacting with said first mentioned cover section for entirely covering the top of a bottle.

12. A bottle carrier and cover comprising a wire arranged in looped formation and having approximately one-half portion thereof arranged at right angles to the other half portion, spring jaws formed upon one angled portion of said wire loop adjacent the point of angle for engaging the neck of a bottle, a cover arranged in sections, one of said sections being carried by the angled portion of said loop having said jaws formed thereon for covering a portion of the top of the bottle, outstanding eyes carried by the other of said sections and receiving the side portions of the angled portion of said loop not having said jaws thereon for slidably supporting said second mentioned cover section for coacting with said first mentioned cover section for entirely covering the top of a bottle.

In testimony whereof, I have affixed my signature.

WILLIAM DONALDSON.
